UNITED STATES PATENT OFFICE

2,559,164

COOLING AND AIR CONDITIONING DEVICE

Donald E. McAllister, Coulee Dam, Wash., assignor of one-half to Vern Enos, Coulee Dam, Wash.

Application November 24, 1948, Serial No. 61,883

1 Claim. (Cl. 261—92)

1

This invention relates to an air conditioning device for vehicles.

An object of this invention is to provide an air conditioning means adapted to be mounted within a vehicle so that the interior of the vehicle may be cooled.

Another object of this invention is to provide a device of this kind which includes means for evaporating water to obtain the desired cooling of air which is passed through a rotating evaporator operated from a suitable operator, such as a hand crank, or other suitable power means. This device may be connected to the air duct of a heater so that the fan associated with the heater will provide the necessary draft of air, or the air intake of the device may be directed forwardly so that the forward movement of the device will provide the necessary air force.

A further object of this invention is to provide an improved evaporating element in the form of a perforate drum having disposed therein a pervious cylinder formed of fibrous material, such as wood or other vegetable fibers, or metal fibers, or compounds thereof.

With the above and other objects in view, my invention consists in the arrangement, combination and details of construction disclosed in the drawing and specification, and then more particularly pointed out in the appended claim.

In the drawing,

Figure 1 is a perspective view of an air conditioning device constructed according to an embodiment of this invention,

Figure 2 is a sectional view taken on the line 2—2 of Figure 3,

Figure 3 is a sectional view taken on the line 3—3 of Figure 2.

Referring to the drawing, the numeral 10 designates generally a housing of substantially rectangular shape, which is formed of a bottom wall 11, opposite side walls 12 and 13, and opposite end walls 14 and 15. A flanged closure or top member 16 is removably mounted on the top of the housing 10. A drum generally designated as 17 is rotatably mounted within the housing 10 and comprises end plates 18 and 19 which are secured to a tubular shaft 20.

The shaft 20 at one end extends through the end plate or head 19 and is rotatably mounted in a bearing 21 which is fixed to the outer side of the end wall 15. The shaft 20 is open at its extended end thereby forming an air intake, and the shaft 20 between the plates 18 and 19 is formed with a plurality of openings 22.

A flexible drive shaft 23 is secured to a bushing

2

24 carried by the end 18 and extends through a bearing 25 secured to the end wall 14. The shaft 23 is adapted to be extended to any desired portion of a vehicle such as the dashboard, and a crank 5 may be mounted on the outer end of the shaft 23 so that this shaft may be manually rotated if desired, or this shaft may be connected to a suitable driving means connected with the vehicle engine.

10 The drum 17 includes a cylindrical screen 26 which is fixed between the end members 18 and 19 and a fibrous cylinder 27 is disposed within the cylindrical screen 26. An L-shaped nipple or pipe 28 is secured to the wall 12, extending laterally from this wall and the upper end of the pipe or nipple 28 has a cap 29 removably mounted thereon. Water is adapted to be discharged into the housing 10 through the filling nipple 28 and the housing 10 is adapted to be filled to substantially the water line 30 indicated in Figure 2.

The wall 12 on the inner side thereof is provided with a longitudinally extending and horizontally disposed baffle 31a, and the wall 13 is also provided on the inner side thereof with a horizontally disposed baffle 31. These baffles 31a and 31 are adapted to prevent undue surging or splashing of the water within the housing 10 as the vehicle moves along the road. A discharge valve 32 is secured to the bottom wall 11 so that the water may be drained from the housing 10.

30 The end wall 14 has extending therefrom an air outlet pipe 33 which may be extended to any desired portion in the interior of the vehicle. It will be understood the intake of shaft 20 will be extended forwardly so that air will be forced into shaft 20 as the vehicle moves along and outlet 33 may either enter the vehicle at any place or may be connected to a heater to give additional air at standing or slow speeds.

In the use and operation of this device, the 40 housing 10 which may be of any suitable size may be disposed at any desired position within the vehicle such as beneath one of the seats or beneath the dash. Water is initially placed in the housing 10 to the level 30 and as the vehicle 45 moves over the road, the drum 17 is slowly rotated so that the air entering the forward or intake end of the tubular shaft 20 will pass through the openings 22 into the interior of the drum 17 and will then pass through the moistened fiber 50 drum or cylinder 27 picking up the moisture and then passing out of the housing 10 through the outlet 33. The fibrous cylinder 27 may be formed of any suitable fibers such as vegetable or metal fibers and is sufficiently pervious so that air may 55 freely pass therethrough.

I do not mean to confine myself to the exact details of construction herein disclosed, but claim all variations falling within the purview of the appended claim.

What I claim is:

An air conditioning apparatus comprising a housing adapted to receive a predetermined quantity of water, a tube open at one end to provide an air inlet and having a plurality of longitudinally and circumferentially spaced air outlet openings therein, journaled for rotation in the end walls of said housing, a drive shaft extending from the closed end of said tube, a pair of circular end plates secured to said tube and spaced from the end walls of said housing, inwardly reverted peripheral edges on said plates, a cylindrical screen positioned between said end plates, an outwardly extending peripheral flange on each end of said screen positioned beneath the reverted edge of the adjacent end plate for securing the screen thereto, a fibrous water pervious cylinder

contained within said screen and spaced from said tube, downwardly inclined horizontal baffles on the opposite side walls of said receptacle each extending to a point closely adjacent said screen, and an air outlet in said receptacle, the level of the water in said receptacle normally being substantially tangential to the lowermost peripheral point of said tube.

DONALD E. McALLISTER.
